CLAIM

The ornamental design for a turbocharger transition section, as shown and described.

DESCRIPTION

FIG. 1 is a perspective view of a turbocharger transition section depicting our new design;

FIG. 2 is a front view thereof;

FIG. 3 is a rear view thereof;

FIG. 4 is a side view thereof;

FIG. 5 is a top plan view thereof;

FIG. 6 is a bottom plan view thereof; and,

FIG. 7 is an additional perspective view thereof.

The broken line portion of the figures is included to show unclaimed subject matter only and forms no part of the claimed design.
